UNITED STATES PATENT OFFICE.

WENDELL HESS, JR., OF TROY, NEW YORK, ASSIGNOR TO W. & L. E. GURLEY, A CORPORATION OF NEW YORK.

RECORDING DEVICE.

981,421.

Specification of Letters Patent. Patented Jan. 10, 1911.

Application filed September 25, 1909. Serial No. 519,554.

To all whom it may concern:

Be it known that I, WENDELL HESS, Jr., a citizen of the United States, residing at Troy, in the county of Rensselaer and State of New York, have invented certain new and useful Improvements in Recording Devices, of which the following is a specification.

This invention relates to recording devices, and has for its object the arrangement and construction of a periodic recording device making a printed record of the position of some body, as, for instance, a float upon the surface of a liquid. When arranged with such float, it becomes an efficient water-stage recorder, and I illustrate and describe the device in this connection, but call attention to the fact that the device is capable of recording the successive positions of any moving body that might be substituted for the float above mentioned.

The general principle upon which the device operates is as follows: A suitable clock mechanism is caused to drive, continuously, a type-wheel, carrying dies, or types, adapted to print time at successive intervals of, say, fifteen minutes. At the termination of each of these time-intervals, the clock closes an electric circuit and causes a hammer or platen to be thrown against the type-wheel, for the purpose of printing upon an interposed ribbon of paper fed along with the time type-wheel. Adjacent to this time type-wheel is a second type-wheel, operatively connected to move with a float or other object, so as to bring to the printing-point appropriate types or dies to indicate the position of the float or other object. This second or "stage" type-wheel is struck by the same hammer or platen, and prints on the same paper ribbon, so that a simultaneous record is taken of time and stage. As the ribbon is fed along with the type-wheel, and as the distance between successive dies is small, a simple feed and economy in the use of tape are secured.

I shall describe the preferred embodiment of the device in connection with the accompanying drawings, wherein:

Figure 1 is a front elevation of the assembled device, the front portion of the case being removed and the batteries omitted; Fig. 2 is a side elevation partly sectional, of the apparatus shown in Fig. 1, the plane of section being on the center-line

of the device; Fig. 3 is an elevation of a fragment of the printing-wheels and hammer; Fig. 4 is a side elevation of the printing-wheels, as shown in Fig. 3; Fig. 5 is a section on the line 5—5 of Fig. 3; and Fig. 6 is a section on the line 6—6 of Fig. 2; Fig. 7 is a detail elevation of the parts comprising the periodic circuit-closing device and the battery wiring, etc.; and Fig. 8 represents a portion of the record tape, showing practically constant water-stage.

Like numerals refer to like parts throughout.

The apparatus is supported in a frame or case 1, usually of wood.

2 is a clock, having the usual dial 3 and hands 4. The movement of this clock is similar in all respects to the ordinary striking clock movement, the clock being arranged to strike one stroke at regular time-intervals, say, on each quarter-hour. This striking mechanism is used as a circuit-closer. The metal clock-frame 5 is connected through binding-post 6 and wires 7 (see Fig. 7) to one terminal of an electric battery 8, carried in a swinging block or bracket 9, pivoted to the frame 1, on a pin or bolt 9^a. This connects the bell-hammer 10 to one of the battery terminals. In the path of backward movement of the hammer is a light leaf spring 11, carried by binding-post 12 and connected by wires 13 through an electromagnet 14, to the other terminal of the battery. As the binding post 12 is insulated from frame 5, the contact of hammer 10 with spring 11 completes a circuit through the battery 8, its connections and the electro-magnet 14, energizing the latter. Thus, the magnet is periodically energized for a short time at regular intervals, the purpose in using the rearward movement of the hammer to effect such energization, being that its motion is then at its slowest, so that a good contact can be secured.

Projecting rearwardly from the clock is an extension 15 of the shaft upon which the hour-hand is mounted. Concentric and in line with this is a shaft 16, carried on the frame 1, and loosely mounted on this shaft 16 are two type-wheels 17 and 18. The wheel 18 is mounted on roller-bearings 19, and is connected by means of a sleeve 20 and pins 21 to the extension 15. Consequently, it revolves with the hour-shaft of the clock.

The wheel 17 is mounted on plain bearings and carries a gear 22, attached thereto by screws 22^a, said gear meshing with a pinion 23, loose on stub-axle 24, carried by frame 1. Fast to pinion 23, is a sprocket 25, over which runs a chain 26 carrying at one end a float 27, and at the other a counterweight 28, to keep the chain taut. As the float 27 rises and falls with the water-level, sprocket 25 will be rotated in one or the other direction, and wheel 17 will be turned through the gear-train to a corresponding position.

Wheel 17 carries types 29, appropriately spaced and bearing the proper numerals or legends to record at the printing-point the various positions of float 27. Wheel 18 carries types adapted to record at the printing point the times in hours and minutes corresponding to the positions of the hour-hand at the various time-intervals marked by the closing of the circuit. These wheels 17 and 18 carry, respectively, ribs 31 and 32, adapted to guide and retain a tape 33 over the type-faces.

The type-wheel 18 is provided with a series of very fine needle points 18^a, projecting beyond its periphery so as to penetrate the record tape 33 (as at 18^b, Fig. 8), and cause it to move with the type-wheel. The diameter over the type faces on wheel 18 may be made slightly larger than the similar measurement on wheel 17, so that the latter may rotate free of the tape.

The ribbon 33 is made up of two strips, the record strip 34 and a carbon paper ribbon 35, or pigment carrier to give the necessary mark when the ribbon is struck against the type-wheels. These two strips are wound together on a spool 36, whence they pass up around the type-wheels and down to a second spool 37. This spool 37 is urged in its winding direction by a weight 38, hung on a cord 39, wound around a drum 40. Connection between the spool 37 and drum 40 is had through a train of gears 41 and 42. The purpose of this driving mechanism is merely to keep the ribbon taut and take the load off the clock mechanism, the real feed of the paper being effected by the time type-wheel 18.

From the above description it is obvious that the proper time type is brought to printing position at the end of each time-interval. At such moment the electric circuit is completed and energizing the magnet causes an impression to be taken on the tape of this time die and the nearest die on the stage type-wheel, through the following instrumentalities:

43 is a bracket carried on frame 1. A short arm 44, of a bell-crank lever pivoted in this bracket, carries an armature 45 adjacent the pole of magnet 14, so as to be drawn down when the magnet is energized. The

long arm 46 of this lever carries a rubber platen 47 and a pin 48. When the arm 44 is drawn down, platen 47 is thrown against the type-wheel, making a record on the ribbon. Pin 48 punctures the paper and accurately indicates the stage, as the platen is apt to cause a series of two or more dies to print because of their closeness on the stage type-wheel. This is clearly indicated in Fig. 8, where the simultaneous printing of several dies is illustrated. The perforation 49 indicates exactly which reading is the one to be taken as corresponding to the time printed by the time-wheel.

It will be noted that the record shown in Fig. 8 indicates no substantial change in the water-stage.

The idea of driving the ribbon constantly and by means of the time type-wheel is important, as simplifying the mechanism and economizing space; also, because if a record is missed, the blank space in the record ribbon will, undoubtedly, call attention to the fact.

When the recorder is positioned, it is necessary to so adjust the stage type-wheel that it shall print the correct designation for the position of the float. To accomplish this purpose it is merely necessary to lift the chain from the sprocket wheel, and turn the type-wheel to the position corresponding to the water stage. The chain is then placed over the sprocket wheel, and the record printed will thereafter be direct reading without correction or computation of any sort.

In the following claims I shall use the words "printing" and "type" in the broad sense, as indicating any method or means for printing, embossing, perforating or otherwise forming upon the record strip legible characters, and I shall use the term "printed record" to indicate a record made as above, as contradistinguished from a continuous record, the latter being a record traced by a stylus and indicating quantity or other conditions by the length of the line so traced, or by its height above a base line, or by similar characteristics of the line, as is common in recording devices.

Having thus described my invention, what I claim is:—

1. In a device adapted to record time and another quantity upon a record sheet, the combination of a movable series of type adapted to print characters representing the time; a second and independently movable series of type adapted to print characters representing said other quantity; and means for moving said record sheet simultaneously and in contact with the time printing type, the characters impressed by each series of type at each recordation being individually legible without computation.

2. In a device adapted to make a printed

130

- record of time and of the positions of an object upon a record sheet, the combination of printing means adapted to print the desired times, said means including a type carrier which also feeds the record sheet; a second type carrier coacting with said printing means adapted to print upon said record sheet characters which represent positions of the object; and connections between said object and the second type carrier whereby the carrier is moved by the object independently of the first type carrier.
3. In a device adapted to make periodic records upon a record sheet, the combination of mechanism adapted to print individually legible characters indicating time; means for driving said record sheet continuously at approximately constant speed; and means movable relatively to the time printing means for printing individually legible characters indicating the quantity recorded.
4. A recording device comprising in combination a type wheel carrying at suitable intervals types adapted to print individually legible characters indicating time; means for driving said wheel at constant and appropriate speed; a second and adjacent wheel movable by the body subject to record; types on said wheel adapted to print individually legible characters indicating corresponding positions of said body; and means for periodically taking an impression of type of each wheel, upon a record strip, as the time types successively reach a predetermined point, said strip passing partially about said wheels.
5. A recording device comprising, in combination, a time-keeping mechanism; a printing-wheel driven by said time-keeping mechanism; a second printing-wheel adjacent said first printing-wheel and movable by the object subject to record; means for feeding a record tape around said printing-wheels and causing it to move with said first printing-wheel; and means for taking periodic impressions of types on said wheels on the record tape.
6. A recording device comprising, in combination, a time-keeping mechanism; a printing-wheel driven by said time-keeping mechanism; a second printing-wheel adjacent said first printing-wheel and movable by the object subject to record; means for feeding a record tape around said printing-wheels and causing it to move with said first printing-wheel; and means, comprising an electro-magnetic hammer controlled by the time-keeping mechanism, for taking periodic impressions of types on said wheels on the record tape.
7. A recording device comprising, in combination, a time-keeping mechanism; a printing-wheel driven by the time-keeping mechanism; a second printing-wheel adjacent the first printing-wheel, of slightly less diameter and movable by the body subject to record; means for feeding a record tape about said printing-wheels and for keeping it in contact with a portion of said first printing-wheel; and means for taking periodic impressions of types on said printing-wheels, upon said record tape.
8. A record feed mechanism for recording devices comprising, in combination, a clock-driven time-printing type-wheel; a loose spool; a geared spool; a drum geared to said geared spool; a cord wound on said drum; and means for exerting tension on said cord, the mechanism being so arranged that a tape may pass from the loose spool around a portion of the type-wheel, move therewith, and then be wound upon the geared spool.
9. A record feed mechanism for recording devices comprising, in combination, a clock-driven type-wheel; a free-turning spool; a second spool; and mechanism tending to rotate said second spool, the above devices being so arranged that a tape may pass from the free-turning spool, around a portion of the type-wheel and move therewith, and then be wound upon the second spool.
10. A recording device comprising, in combination, a time-keeping mechanism; a series of time-printing dies driven by said time-keeping mechanism; a second series of printing dies adjacent said first series and movable by the object subject to record; means for feeding a record tape in contact with said time-printing dies and causing it to move therewith; and means for taking simultaneous impressions of dies in the two series upon the record tape.
11. In a recording mechanism comprising a clock, printing dies controlled thereby, and printing dies controlled by the object subject to record; a device for taking periodic impressions of said dies upon a record strip, comprising, in combination, a lever, pivotal mountings for said lever, a suitable platen carried by said lever, an armature fast to said lever, an electro-magnet adjacent said armature, a source of electric current, an arm movable by said clock at certain time periods, a contact-piece in the path of said arm, and suitable connections whereby the contact of said arm with said contact-piece completes a circuit through the electro-magnet.
12. In a recording device adapted to make a printed record of time and of another quantity upon a record sheet, printing type; means for supplying a pigment carrier to said type; and a plurality of pins moving with said type and engaging said sheet to move the latter, said pins being formed separately from the type.
13. A recording device comprising, in combination, a time-keeping mechanism; a printing-wheel driven by the time-keeping mechanism; a plurality of sharp pins pro-

- jecting from the face of said type wheel; a second printing-wheel adjacent the first printing-wheel, of slightly less diameter and movable by the body subject to record; 5 means for feeding a record tape about said printing-wheels and for keeping it in contact with a portion of said first printing-wheel; and means for taking periodic impressions of types on said printing-wheels, 10 upon said record tape.
14. In a recording device, a time keeping mechanism; a printing wheel operatively connected thereto; and a record feeding mechanism adapted to hold a record sheet 15 in contact with said printing wheel and to urge it in the direction of movement of the printing wheel.
15. In a recording device, the combination of a series of printing dies; means for moving said dies at uniform speed in a given 20
- direction; and a record feeding mechanism adapted to hold a record sheet in contact with the dies and to urge it in the direction of movement of the dies.
16. In combination with a time keeping 25 mechanism, a printing wheel operatively connected thereto; a plurality of pins projecting beyond the face of the printing wheel; and a record feeding mechanism adapted to hold a record sheet in contact 30 with said pins and to urge said sheet in the direction of movement of the printing wheel.
- In testimony whereof I have signed my name to this specification in the presence of two subscribing witnesses.
